UNITED STATES PATENT OFFICE.

FREDERICK W. FRANKLIN AND WILLIAM F. FLAGGS, OF BALTIMORE, MD.

STOCK-CAR.

SPECIFICATION forming part of Letters Patent No. 254,949, dated March 14, 1882.

Application filed January 10, 1882. (No model.)

To all whom it may concern:

Be it known that we, FREDERICK W. FRANKLIN and WILLIAM F. FLAGGS, citizens of the United States, residing at Baltimore, in the 5 State of Maryland, have invented certain new and useful Improvements in Stock-Cars, of which the following is a specification, reference being had therein to the accompanying drawings.

10 Our invention relates to certain improvements in cars for the transportation of live stock, such as horses, cattle, sheep, and swine.

The construction of a car embodying our improvements will first be described, and the invention will then be designated in the claims.

15 In the drawings hereto annexed, Figure 1 is a side view of a car embodying our improvements designed for cattle. Fig. 2 is a horizontal section of one end of the car, taken at line *x* of Fig. 1. Fig. 3 is a detail view, showing a vertical section of the top part of the water-tank and its inlet-cap. Fig. 4 is a vertical cross-section of the car designed for cattle. Fig. 5 is an end view of the car, showing 25 the position of the several parts. Fig. 6 is a vertical cross-section of a car with our improvements, having two floors or two decks, designed for sheep and swine. Fig. 7 is a side view of one end of the car shown in Fig. 6.

30 The letter *A* designates the floor of an ordinary stock-car, *B* the sides, and *C* the roof or top. At each end of the car a water-tank, *D*, is placed. We design these tanks to occupy the entire width of the car end, and in height 35 to extend from a point just above the top of the water-troughs, where the bottom of the tanks will be located, to the roof of the car. The dimension of these tanks in the direction which extends lengthwise of the car may vary. They

40 may be larger or smaller; but a suitable size ordinarily would be from twelve to fifteen inches. These tanks may be placed on the inside of the wall of the car or upon the outside of the wall, as shown in the drawings. An inlet, *a*, is provided at the top of each tank, through which the tank may be supplied with water. This inlet is closed by a tight-fitting hinged cap, *b*. The tank is provided with two vertical partitions or diaphragms. (Indicated 45 by the broken lines *c* in Fig. 5.) These extend

from near the bottom to near the top, and divide the tank, as it were, into three compartments; but the water at all times has free access from one compartment to the other by the opening below the partitions, and, when 55 the tank is full, by the openings above the partitions. These partitions serve to stay and strengthen the broad sides of the tank and prevent them from bulging out, and also to restrict the water from moving too freely or sloshing 60 about in the tank when the car is under way. The two tanks, one being at each end of the car, are connected by means of a pipe, *E*. This pipe is preferably arranged in the top of the car below the roof, and each end of 65 the pipe enters one of the tanks near the top. By this arrangement both tanks may be filled by entering the water into either one, and thus a shifting of the car to bring each end thereof alternately before the water cistern or supply 70 pump to fill each tank separately is avoided. It will be seen that when one tank is full the water will overflow into and pass through the pipe *E* to the other tank and fill it.

Extending along each side of the car, at a 75 suitable height from the bottom, is a water-trough, *F*, made of any suitable material or any suitable shape. One side of the trough has notches or recesses *d*, which receive the vertical studs *e* of the side wall of the car. By 80 this arrangement the trough can be located so that its longitudinal center will come fairly on the line of the wall of the car, or, in other words, about one-half of the width of the trough is upon the inner side of the wall of the car 85 and about one-half outside of the wall. From the center of the bottom of each tank is an outlet, which is regulated by a globe-valve, *f*, the stem or handle *f'* of which projects from the rear. From this valve two pipes, *g*, branch 90 in opposite directions, one leading to each of the troughs. By this arrangement the troughs on the opposite sides may be replenished simultaneously by opening the one valve.

Along the sides of the car, over the water-trough, one or more boards, *h*, are arranged in a slanting position, as shown in Fig. 4, and form the inclosure or wall of the car above the outer edge of the trough. This arrangement increases the space inside of the car and over 95 100

the open top of the trough, and this enlargement of the space affords room for the movement of the head of the animal.

A horizontal projecting rail, I, is attached to 5 the sides of the car just above the slanting boards. This rail projects inward from the wall of the car about as far as the inner edge of the water-trough, and is located above the car-floor at such a height that the hip of full-grown cattle will come against it. Thus it 15 will be seen the rail serves as a fender or guard to keep the cattle off the water-trough, and so prevent it from becoming foul.

At the upper end of each tank, and at the 15 side opposite that at which the pipe E is attached, is an outlet, k, to which a short pipe, n, connects. This pipe may be closed by a suitable cap when not otherwise used; but the object of this short pipe is to permit the tanks 20 of one car to be so coupled with the tanks of another car that a water communication between them may be established at the time of filling the tanks. This coupling is effected by means of the short flexible tube or hose n', 25 and this arrangement serves to so connect the tanks that it is possible to fill all the tanks of several cars by simply entering the water from the cistern or supply-pump into any one of the tanks and allowing it to flow therefrom through 30 the hose n' into the others.

Another feature of our improvement in stock-cars consists of the door. This consists of a sliding door, P, to close the upper part of the doorway, and the hinged door q, to close the 35 lower part, whereby the hinged door serves as a bridge from the car-floor to the stock-pen or platform, whereat the animals are loaded onto or discharged from the car. The upper door slides to one side of the doorway on a rail in 40 the usual manner of car-doors, and the lower door is hinged at its lower edge to the frame or floor of the car, so as to turn down, as indicated by broken lines in Fig. 1, and as seen in Fig. 5.

45 For sheep and swine the car may be constructed with two floors or two decks, as shown

in Figs. 6 and 7. In this case two tanks are needed at each end of the car—one for each floor. The upper tank may connect with the lower one, and the connection be provided with 50 a valve, so as to keep water in the upper one when it is drawn from the lower one; or both the upper and lower tank may each have an inlet to receive a supply of water direct from the cistern or pump.

55 Instead of the long continuous troughs as shown, we contemplate the use of a separate trough for each animal. These separate troughs may be arranged on the side of the car at proper intervals, and each supplied by a pipe extending along the side. This arrangement would be particularly suited for horses, and for their still further accommodation and protection the car might be divided into stalls or compartments, so that each horse could be kept separate from the others.

Having described our invention, we claim and desire to secure by Letters Patent of the United States—

1. In a stock-car, a water-tank to occupy 70 the entire width of the car end, and provided with vertical partitions, the edges of which are attached to the two opposite broad sides of the tank, said partitions extending from near the bottom to near the top, leaving openings below and above, by which the water may have access from one side of the partition to the other, as set forth.

2. In a stock-car, the combination of a water-trough on the side of and located partly outside 80 of the wall of the car, a slanting board which extends from the wall of the car to the outer top edge of the trough, and a horizontal rail to serve as a hip-fender, as set forth.

In testimony whereof we affix our signatures 85 in presence of two witnesses.

FREDERICK W. FRANKLIN.
WILLIAM F. FLAGGS.
